UNITED STATES PATENT OFFICE.

AUGUSTINE F. LITTLEFIELD, OF LYNN, MASS., ASSIGNOR TO GOODYEAR
& MCKAY SEWING MACHINE COMPANY, OF HARTFORD, CONN.

MACHINE FOR BEATING OUT WELTS.

SPECIFICATION forming part of Letters Patent No. 320,075, dated June 16, 1885.

Application filed March 23, 1885. (No model.)

To all whom it may concern:

Be it known that I, AUGUSTINE F. LITTLEFIELD, of Lynn, in the county of Essex, State of Massachusetts, have invented an Improvement 5 in Machines for Beating Out Welts in the Manufacture of Boots and Shoes, of which the following description, in connection with the accompanying drawings, is a specification, like letters on the drawings representing like 10 parts.

In the manufacture of that class of boots and shoes known as "welted work" the welt stitched to the upper and to the inner sole has to be hammered or beat out by hand in order 15 to make the same smooth and level, that it may lie properly upon the outer sole, to which it is to be attached by stitches or otherwise.

The object of this invention is to provide a machine to automatically perform this class of 20 work.

This invention consists, essentially, in an automatically-operated hammer, combined with a welt-support or wheel the edge of which is reduced to extend between the upper 25 and its attached welt, substantially as will be described.

Figure 1 is a side elevation and partial section representing a machine embodying my invention, the shoe being shown in section 30 with the welt in position to be hammered or beat out. Fig. 2 is a rear or right-hand end elevation of Fig. 1.

The frame-work A has bearings A' A' for the main shaft A², upon which is secured the 35 recessed part B of a clutch-pulley, the other part, B', of which is mounted loosely on the said shaft, and is grooved at B' to receive a driving-welt and at B² to receive a pin, 2, projecting therein from the forked upper end of 40 the lever C, pivoted at C' on an extension of the frame-work, the inner arm of the said lever having connected with it a rod, C², which by a suitable link, C³, is joined with any usual treadle mechanism, (not shown,) by which at 45 will the part B' of the clutch rotated continuously by a belt may be forced into contact with the clutch part B fast to the shaft A², to rotate the said shaft. The shaft A², at its front

end, has a disk, A³, provided with a crank-pin (shown in dotted lines, Fig. 1) which enters a 50 link, D, which in turn is applied to a stud, D', of a loose sleeve, D², extended from the rod E, which at its lower end has attached to it the hammer E'. The rod E is adapted to slide in the bearings A' A' of the frame-work 55 and has applied to it two fast collars, a b, and between the collar b and the lower end of the loose sleeve D² the rod has applied to it a strong spiral spring, c, so that the blow of the hammer is made yielding, or so that the hammer 60 may yield to the differing thickness of material under it when the thickness or solidity of the material demands. The frame-work is provided with a vertical stud, (shown in dotted lines, Fig. 1,) on which is placed 65 loosely a welt-support, G, made as a wheel having a thin V-shaped edge, 5, which is adapted to be inserted into the space between the welt w and upper u, attached to the inner sole, i, by the stitches s. When the shoe is 70 held as in Fig. 1, the welt w may be placed between the welt-support G and the hammer E', when it will be subjected to a series of rapid blows so long as the clutch-pulley B B' is kept in rotation. The rod E, at its upper 75 end, is provided with a fixed collar, h, which is provided with a hole to receive loosely the pin h', attached to the frame-work, the said pin and collar preventing revolution of the rod E. The spring h² acts normally to keep 80 the clutch parts B B' separated. The collar m prevents the withdrawal of the pulley B' from the shaft A².

I claim—

1. In a machine for beating out welts attached to the uppers and soles of boots and shoes, the welt-support shaped to enter the space between the upper and its attached welt, combined with the automatically-reciprocated hammer to hammer the said welt, substantially as described.

2. The shaft A², the clutch-pulley B B', the rod, sleeve D², connecting devices between them, and the spring and collars a b, and the hammer, combined with the welt-support 95 having a thin or V-shaped edge to enter be-

tween the welt and upper, substantially as described.

3. The hammer carrying bar provided with the two collars or shoulders *a b*, and the 5 sleeve, and means, substantially as described, to move it, combined with the spring *c* and with the support *G*, to operate as set forth.

In testimony whereof I have signed my name to this specification in the presence of two subscribing witnesses.

AUGUSTINE F. LITTLEFIELD.
